UNITED STATES PATENT OFFICE.

THOMAS ORDE SMITH, OF OAKLAND, CALIFORNIA.

DESIGN FOR A BOTTLE.

49,076.

Specification for Design.

Patented May 16, 1916.

Application filed March 9, 1916. Serial No. 83,201. Term of patent 7 years.

To all whom it may concern:

Be it known that I, THOMAS ORDE SMITH, a subject of the King of England, residing at Oakland, Alameda county, and State of California, have invented a new, original, and ornamental Design for Bottles, of which the following is a specification.

In the accompanying drawing, which is made a part hereof and to which reference is made, Figure 1 is a perspective view of the bottle complete, Fig. 2 a side elevation thereof, Fig. 3 a plan view of the top of said bottle, and Fig. 4 a cross section looking downward from the dotted line 4—4 in Fig. 2.

The shape or form and ornamental character of the bottle will be made clearly apparent from said drawings.

What I claim is:

The ornamental design for a bottle shown in the accompanying drawings.

In witness whereof, I have hereunto set my hand and seal at San Francisco, California, this 8th day of February, A. D. nineteen hundred and fifteen.

THOMAS ORDE SMITH. [L. S.]
